UNITED STATES PATENT OFFICE.

CHARLES S. BEEBE, OF RACINE, WISCONSIN, ASSIGNOR TO B. B. MANUFACTURING COMPANY, OF RACINE, WISCONSIN, A CORPORATION OF WISCONSIN.

SLED.

1,253,338.

Specification of Letters Patent. Patented Jan. 15, 1918.

Application filed April 30, 1917. Serial No. 165,363.

To all whom it may concern:

Be it known that I, CHARLES S. BEEBE, a citizen of the United States, residing at Racine, in the county of Racine and State of Wisconsin, have invented certain new and useful Improvements in Sleds, of which the following is a specification, reference being had to the accompanying drawing, forming a part thereof.

10 This invention relates to sleds and the object of the invention is to improve the construction of sleds in the manner to be hereinafter described and claimed.

Referring to the drawings which accompany this specification and form a part hereof, which drawings illustrate an embodiment of this invention, and on which drawings the same reference characters are used to designate the same parts wherever 20 they may appear in each of the several views, Figure 1 is a side elevation of the sled; Fig. 2 is a plan view of the sled and Fig. 3 is a transverse section of the sled on the line 3-3 on Fig. 1, looking in the 25 direction indicated by the arrows.

Referring to the drawings, the reference numerals 1 and 2 designate runners. These runners are preferably made from angle iron, as clearly shown by the drawings and 30 have substantially horizontal central parts with upwardly curved front ends similar in these respects to ordinary sled runners. The rear ends of the runners are bent upwardly rather abruptly to form inclined parts 3 for 35 a purpose to be hereinafter described. The front ends of the runners are united by a bar 4, which is connected to the front ends of the runners by bolts or pivots 5 and 6. Running boards 7 and 8 are secured to the 40 runners 1 and 2 in any suitable manner as, for example, by the rivets 9 and 10 and angle irons 11 and 12, which are secured to the running boards and the runners by rivets, as clearly shown by the drawings. The angle irons 11 and 12 are located about mid- 45 way of the lengths of the runners and the runners are free to be bent or flexed side- wise in front of these angle irons in the manner to be hereinafter described. The 50 front ends of the running boards 7 and 8 are bent upwardly, following the general curves of the front ends of the runners, to provide foot-rests 13 and 14. A seat 15 is supported near its rear end by a bent bracket 55 16, which is preferably secured to the seat

by a single rivet or bolt 17 and which is secured to the running boards 7 and 8 by rivets 18 and 19. In the construction shown by the drawings, the running boards 7 and 8 are made of wood and at their front ends they 60 are provided with metal tips 20 and 21 riveted thereto and bent around a rod 22, which passes through the seat 15. The ends of the rod 22 may be upset or headed over against washers 23 and 24. Metal straps 25 and 26 are pivoted to the seat 15 by a single pivot 27 and are also pivoted to the bar 4 by a single pivot 28. A steering yoke 29 is rigidly fastened to the metal straps 25 and 26 so that pressure against either end of the 70 steering yoke will rock the metal straps 25 and 26 about the pivot 27 and move the bar 4 sidewise and bend or flex the runners sidewise forward of the angle irons 11 and 12. In the construction illustrated by the 75 drawings, the steering yoke 29 is secured to the metal straps 25 and 26 both by the pivot 28 which extends through the bar 4, and by the bolt 30. The ends of the steering yoke 29 may be provided with holes 31 and 32 for 80 attaching a rope thereto.

A handle 33 is pivoted upon the rod 22 so that it can be lowered flush with the seat 15 or can be raised to an elevated position. In the construction illustrated by the draw- 85 ings, the handle is composed of two members 34 and 35 located on opposite sides of the seat 15 and united by a bar 36. A button 37 pivoted on the rivet or bolt 17 can be turned so as to hold the handle flush with 90 the seat, or can be turned so as to release the handle. The metal tips 20 and 21 are pro- 95 vided with parts 38 and 39 which project out into the path of movement of the handle, as it is swung upwardly around the rod 22, 95 to serve as stops to limit the movement per- mitted to the handle, so that the handle can afford a rigid brace for the user of the sled. When the handle is lowered flush with the 100 seat 15, the members 34 and 35 rest upon the top part of the bent bracket 16 as clearly shown by Fig. 3 of the drawings. In the use of the sled, the user can sit upon the seat 15, and the handle 33, with his feet upon the horizontal parts of the running boards 105 or against their foot-rests 13 and 14. The sled can be steered by bending or flexing the runners either by pressing with a foot against the steering yoke 29 or pulling on rope 40 secured thereto. By standing on the 110

running boards, the sled can be operated by standing on the running board and the user can have practically all the pleasure of skeeing and can either coast with his hands free or can maintain his balance by means of the rope 40 or the handle 33. By providing the stops 38 and 39 for the handle 33, a rigid support is obtained for the handle, which makes it safe for small children to coast on the sled in a standing position. The sled can also be used in the same manner as an ordinary sled.

It will be noticed particularly from inspection of Figs. 2 and 3 of the drawings that the total width of the seat 15 and handle 33 is the same as the distance between the running boards 7 and 8 and, as the seat is elevated above the running boards, it provides a support which can be gripped between the legs of the rider, when he is standing up on the running boards, so that he can maintain his position more securely.

If the user desires to stop the progress of the sled, he can shift his feet back on the running board so that his weight will be over the rear inclined parts 3 of the runners and thereby tilt up the front end of the sled and produce a braking effect in the same general manner that a skater sometimes tilts his skates to slow down or stop.

If the sled is used on snow soft enough to permit the runners 1 and 2 to sink in until the sled is supported by the running boards 7 and 8, the running boards 7 and 8 will act as skees and, being fastened to-

gether, all the pleasures of skeeing can be enjoyed by inexperienced or young persons, so the running boards 7 and 8 can also be designated as skees.

What is claimed is:

1. In a sled, the combination with a seat, of running boards below the seat and at the sides thereof and provided with upwardly inclined parts, and runners below the running boards.

2. In a sled, the combination with a seat, of running boards below the seat and at the sides thereof and provided with upwardly inclined parts, runners below the running boards and with their forward ends free to be flexed sidewise, and means for flexing the forward ends of the runners sidewise.

3. In a sled, the combination with a seat and running boards, of runners below the running boards and having their rear ends inclined upward.

4. In a sled, the combination with a seat and running boards below the seat and at the sides thereof, of a handle adapted to be turned into the plane of the seat or to be raised above the seat.

5. In a sled, the combination with a seat, running boards and runners, of a rigid handle pivoted to the seat so that it can be turned down flush with the seat or elevated above the seat, and a stop for the handle when in its elevated position.

In witness whereof I hereto affix my signature.

CHARLES S. BEEBE.
